United States Patent Office

Des. 215,222

Patented Sept. 16, 1969

215,222

GAME BOARD

James H. Nicholas, 115 S. Macomb St.,
Monroe, Mich. 48161

Filed Aug. 15, 1968, Ser. No. 13,145

Term of patent 14 years

Int. Cl. D21—01

U.S. Cl. D34—5

Fig. 1

Fig. 2

I claim:

The ornamental design for a game board, substantially as shown.
